UNITED STATES PATENT OFFICE.

IVAR LUNDGAARD, OF HARTFORD, CONNECTICUT, ASSIGNOR, BY MESNE ASSIGNMENTS, TO DEVON MANUFACTURING COMPANY, OF BOSTON, MASSACHUSETTS, A CORPORATION OF MASSACHUSETTS.

REFRIGERATING MACHINE.

Application filed February 7, 1924. Serial No. 691,165.

This invention relates to automatic refrigerating machines involving the use of air as a medium, such as is shown in my prior Patent No. 1,240,862.

5 My present invention relates more particularly to a means of increasing the average pressure of the mediating air and to this end, it comprises an auxiliary air pump, mounted in the crank case and articulated 10 with the moving members of the air compressing mechanism, which pump operates to draw air from the atmosphere and force the same into the crank case, thereby keeping the pressure in the crank case a definite 15 amount above atmospheric pressure. As the pressure in the crank case is the minimum pressure of the air compressing cycle, the average pressure of the cycle is, therefore, raised, by means of the auxiliary pump, 20 any desired amount.

In the drawings:

Figure 1 represents a section through the portion of the crank case, upon which the pump is mounted at right angles to the driving 25 shaft.

Figure 2 is a section through the pump parallel with the driving shaft.

Figure 3 shows a modification.

In the embodiment shown in the drawings, 30 1 represents the driving shaft of the refrigerating machine and 2 the ends of connecting rods articulated therewith and being driven thereby. 3 represents a crank case of the refrigerating machine and in a depressed portion of the bottom of the same is attached the cylinder 4 of the auxiliary pump. A piston plunger 5 is adapted to be reciprocated in the cylinder by means of the cross head 6 and connecting link 7, which 35 unite the same to the corner of the aforesaid connecting rod 2. From this it will be seen that the rocking motion of the connecting rod will impart a reciprocating motion to the plunger 5. Air is admitted to the pump 40 from the atmosphere through a calcium chloride box 8, wherein the air is freed of its moisture before entering pipe 9, which leads to a vertical duct 10, the lower end of which dips into a mercury seal 11. At the 45 lower end of the duct, a ball 12 may be used to check the outflow of air from the pump. The height of the mercury column in the

duct 10 will also act as a check. The casting 13, surrounding the duct 10 and holding the mercury trap, opens into a duct 14 55 that leads to the pump cylinder. A discharge duct 15 leads from the pump cylinder into the crank case and has a check valve 16 for preventing the air returning from the crank case to the cylinder. This duct 15 extends into the cylinder chamber to a point near the bottom. This is in order to insure that any oil in the cylinder will be driven out in advance of the air. The volume of the clearance in the cylinder, in the duct 14 60 and in the chamber 13, should be made such that the pressure established in the crank case by the pump will not be too great and it will be seen that the fixing of this volume establishes definitely the maximum pressure 65 to be attained in the crank case. It becomes important, therefore, to prevent any accumulation of oil in the clearance space as such accumulation would, of course, bring about a decrease in the clearance and an increase 70 in the delivery pressure. It will be apparent also that any surplus oil running into the suction chamber 13 will be immediately pumped out and into the crank case. The bottom of the crank case will always contain 75 considerable oil, which serves to lubricate the moving parts of the machine. From the crank case, the air passes to the cylinder by duct 16 in the side of the cylinder wall 17, when the piston 18 is at its lowermost 80 position. If desired, the ball check, shown at 12, may be omitted, in which case the mercury column 11 will act to prevent any escape of air during the pressure stroke of the pump. On the suction stroke, the mercury will all run out of the duct 10 and will 85 allow the admission of the air. Owing to the relative sizes of the chamber 13 and the column 10, very little change in level of the mercury in the chamber will correspond with a considerable change in the height of the mercury column 10. The height of this column of mercury may also be used as a means of regulating and limiting the maximum pressure. To make this more definite, means should be provided for limiting the height 90 of the mercury column and to this end there is provided an enlargement of the suction conduit at 19 so that when the mercury

reaches that point, it will spread out horizontally and prevent a further increase in head.

In Figure 3 is shown a modified form in which the pump plunger 5 is made hollow so as to form the delivery outlet for the pump. The check valve 16 is in this case located in the plunger. To guard against possible leakage of air or oil past the plunger, affecting the clearance, the base of the pump may be formed with a trapped recess 20 formed, for example, by a depending flange 21. With such a construction, the clearance and, consequently, the maximum pressure of air delivered by the pump into the crank case will remain fixed and will not be affected by leakage past the plunger or valves.

I claim:

1. In a machine of the class described comprising a crank, a crank-case and a connecting rod connected to said crank, the combination with the crank-case of an auxiliary air pump adapted to receive atmospheric air and having an outlet port leading into the crank-case.

2. In a machine of the class described comprising a crank, a crank-case and a connecting rod connected to said crank, the combination with the crank-case of an auxiliary air pump adapted to receive atmospheric air and having an outlet passage into the crank-case, said passage connecting with the clearance chamber of the pump near the lowest part thereof, whereby surplus oil in said chamber will be expelled into the crank-case.

3. In a machine of the class described comprising a crank, a crank-case and a connecting rod connected to said crank, the combination with the crank-case of an auxiliary air pump adapted to receive atmospheric air and having an outlet port leading into the crank-case, said pump being located substantially below the normal oil level of the crank-case.

4. In a machine of the class described comprising a crank, a crank-case and a connecting rod connected to said crank, the combination with the crank-case of an auxiliary air pump adapted to receive atmospheric air and having an outlet port leading into the crank-case, and a check valve in the outlet port adapted to permit flow of air into the crank-case at a determined differential in pressure between the chamber of the pump and the crank-case.

5. In a machine of the class described comprising a crank, a crank-case and a connecting rod connected to said crank, the combination with the crank-case of an auxiliary air pump adapted to receive atmospheric air and having an outlet passage into the crank-case, said pump being provided with a clearance chamber and a plunger reciprocable therein, said passage connecting with the clearance chamber of the pump near the lowest part thereof, whereby surplus oil in said chamber will be

expelled into the crank-case, so as to maintain a constant clearance volume.

6. In a machine of the class described comprising a crank, a crank-case and a connecting rod connected to said crank, the combination with the crank-shaft, of a connecting rod and a link both operatively connected to said shaft, an auxiliary air pump, a plunger in said pump connected to the link, said pump having a port connected to the outer air and a second valve-controlled opening leading into the interior of the crank-case.

7. In a machine of the class described comprising a crank, a crank-case and a connecting rod mounted thereon, the combination of an auxiliary air pump, a plunger in said pump, a link operatively connected to said plunger and articulated to said connecting rod, a dryer, said plunger having a port connected to the dryer and adapted to receive dried outer air therefrom and having a weighted check valve to permit air outlet into the machine.

8. In a machine of the class described comprising a crank, a crank-case and a connecting rod mounted upon the crank, an auxiliary air pump, a clearance chamber in said pump, a plunger reciprocable therein, connecting linkage between said crank and said plunger for reciprocating the latter in response to rotation of the former, said pump being located in the crank case substantially below the lowest position of the connecting rod, whereby oil having a level sufficiently high to be thrown by the connecting rod dip will cover the pump and act as an oil seal for the same.

9. In a machine of the class described comprising a crank, a crank-case and a connecting rod mounted upon the crank, the combination of the crank-shaft, a link operatively connected to said shaft, an auxiliary air pump, a plunger in said pump connected to the link, said pump having a port connected to the outer air and a valve-controlled opening leading into the interior of the crank-case, said valve being adapted to open when the pressure in the pump exceeds the pressure in the crank-case by a predetermined amount.

10. In a machine of the class described comprising a crank, a crank-case and a connecting rod connected to the crank, an auxiliary air pump, a clearance chamber in said pump, a plunger reciprocable therein, a valve controlled outlet connecting the clearance chamber with the interior of the crank case, means for actuating the plunger connected to the crank, said outlet being located in the crank case below the lowest position of the connecting rod, whereby oil having a level sufficiently high to be thrown by the connecting rod dip will cover the outlet of the pump and act as an oil seal for the same.
